UNITED STATES PATENT OFFICE.

GEORGE COLEMAN, OF RETRO, TENNESSEE.

ATHLETIC-SHOE SPIKE.

1,149,186.

Specification of Letters Patent.

Patented Aug. 10, 1915.

Application filed December 15, 1909. Serial No. 533,148.

To all whom it may concern:

Be it known that I, GEORGE COLEMAN, a citizen of the United States, residing at Retro, in the county of Hamilton and State of Tennessee, have invented new and useful Improvements in Athletic-Shoe Spikes, of which the following is a specification.

My invention relates to improvements in athletic shoe spikes and more especially to spikes of the type used by baseball players.

Serious injury is often suffered by baseball players because of gashes and scrapes received from the sharp pronged spikes now ordinarily worn, and these injuries are often aggravated by the dirt, etc., lodging in the bruised portions and developing blood poison or kindred diseases.

The primary object of my invention is to provide an improved spike that will prevent these injuries, 1st by providing a spike without prongs or points that will cut a player, and 2nd by providing a self-cleaning spike to which the dirt, etc., will not cling.

With these and other objects in view my invention consists in the novel construction and arrangement of elements hereinafter illustrated and described, and particularly pointed out in the subjoined claims.

Reference is had to the accompanying drawings illustrating what I consider to be the best form of my invention, and in which—

Figure 1 is a side elevation of a baseball shoe provided with sole and heel spikes constructed in accordance with my invention. Fig. 2 is a bottom plan view thereof, broken away in parts, and Fig. 3 is a section through the sole spike, taken on the line 3—3 of Fig. 2.

Like reference numerals indicate corresponding parts throughout the several views.

In the drawings, 5 designates an athletic shoe of any desired type provided with a sole-spike 6 and a heel-spike 7. Except as regards the general contour of these spikes they may be of the same construction or design. In general the heel-spike is shaped to conform with the heel of the shoe and the sole-spike is secured to the sole of the shoe at the "bend" thereof, or directly below the ball of the foot.

Each spike is composed of an earth-gripping member or spike 8 which is preferably formed of sheet metal. A plurality of ears 8^a, which project inwardly from one edge of

each member, are employed for securing the same in place. Each member is bowed and has its outer, or earth-gripping edge, upwardly inclined from its ends toward the center. A transverse pin 10 has its ends respectively journaled in the ends of the said member, and a plate 9, constituting a combined guard and cleaner, is hinged at one end to the said pin. This plate fits snugly within and normally lies close to the inner wall of the member at its outer edge.

A spring 12 is arranged between the shoe and the guard-plate 9, in the illustrated embodiment of the invention being shown as of a V-shape and having bifurcations or arms 13 and 14 at its upper and lower ends respectively. The lower bifurcations 13 are secured to the guard-plate 9 by means of rivets 15, or any other suitable fastening means. The ends of the upper bifurcations or arms 14 are adapted to enter notches 16 in the gripping member 8, or may be secured directly to the sole or heel of the shoe.

When the player stands or runs the pressure of the foot causes the gripping member 8 to enter the ground, depressing the guard-plate 9 against the pressure of the spring 12, the edge of the gripping member affording a substantial hold and enabling the player to quickly start or stop. The moment the shoe is lifted from the ground the spring 12 acts to throw the guard-plate into its normal position flush with the edge of the gripping member, forcing out all dirt and forming a guard for the edge of the gripping member.

It will also be noted that one of the members or spikes 8 is arranged toward the front or toe, on the sole, and the other toward the rear on the heel, the former assisting a player in running, and the latter in stopping. Furthermore, by reason of the fact that the outer edge of each member is upwardly inclined from the instep, a more even tread is provided for the player.

The majority of injuries received from athletic shoe spikes are inflicted by the shoe when raised from the ground, as when a player is "sliding" to a base, and the protection given to the edge of the spike when off the ground is sufficient to prevent the cutting or gashing of the players.

The movement of the spring-pressed plate 9 and its position against the inner wall of the gripping member will prevent the entrance of dirt into the space between the

guard-plate and the shoe, so that the clogging of the operating parts is effectively prevented.

In the event that my improved spike should cut a player, the absence of dirt, etc., around the cutting edge would minimize the seriousness of the injury and materially lessen the danger from complicating dis-eases.

10 It will thus be seen that I have provided an athletic shoe spike embodying the useful features of the ordinary spike, but without its attendant disadvantages.

15 While the structure herein illustrated and described is well adapted to accomplish the several purposes of my invention, it is to be understood that various changes may be made within the scope of the claims without departing from, or sacrificing any of the advantages of the invention.

20 Having now described my invention what I claim as new and desire to secure by Letters Patent is:—

1. An athletic shoe-spike comprising an 25 earth-gripping member having an edge, and a plate hinged at the end to the member and having its free end positioned to automatically guard the said edge of the member.

2. An athletic shoe-spike comprising an 30 earth-gripping member having an edge, and a guard-plate hinged at one end to the member and having its free end adapted to normally fit flush with the said edge of the member.

3. An athletic shoe-spike comprising an 35 earth-gripping member having an edge, and a spring-pressed guard-plate hingedly connected at one end to the member and having its free end adapted to normally fit flush with the said edge of the member.

4. An athletic shoe-spike comprising a 40 bowed earth-gripping member having an edge, and a movable guard-plate for the edge arranged within the said member.

5. An athletic shoe-spike comprising a 45 bowed earth-gripping member having an edge, and a guard-plate for the edge hinged to, and fitting within the said member.

6. An athletic shoe-spike comprising a 50 bowed earth-gripping member having an edge, and a spring-pressed guard-plate fit-

ting within said member and normally lying close to the said edge of the member.

7. An athletic shoe-spike comprising a bowed earth-gripping member having an 55 edge, and a guard-plate for the edge hingedly secured between the ends of the member.

8. An athletic shoe-spike comprising a bowed earth-gripping member having one 60 edge upwardly inclined from each end toward the center, and a guard-plate for the edge hinged to and fitting within the said member.

9. An athletic shoe-spike comprising a 65 bowed earth-gripping member having one edge upwardly inclined from each end toward the center, and a guard-plate for the edge hingedly secured between the ends of the member.

70 10. An athletic shoe-spike comprising a bowed earth-gripping member having one edge upwardly inclined from each end toward the center, a transverse pin journaled in the ends of the member, and a plate having one end hinged to the pin and its other end fitting within the member and normally arranged flush with the edge thereof.

11. An athletic shoe-spike comprising a bowed earth-gripping member having one 80 edge upwardly inclined from each end toward the center, a transverse pin journaled in the ends of the member, a plate having one end hinged to the pin and the other end snugly fitting within the member, and a 85 spring for normally holding the plate flush with the edge of the member.

12. An anti-slipping device for shoes, comprising a plate adapted to be secured upon the sole of a shoe, having a substantially crescent-shaped projecting rigid blade, 90 said blade diminishing gradually in depth from the middle toward each end, the edge of said blade being regular and unbroken.

95 In testimony whereof I have hereunto set my hand in presence of two subscribing witnesses.

GEORGE COLEMAN.
